Primary Examiner — Lucy Lieberman(74) *Attorney, Agent, or Firm* — Sughrue Mion, PLLC(57) **CLAIM**

The ornamental design for a wristwatch, as shown and described.

DESCRIPTION

FIG. 1 is a perspective view of the front and right side of a wristwatch showing my new design; and,

FIG. 2 is a front elevational view thereof.

The broken lines in the drawing figures show environmental structure only, and form no part of the claimed design.
